(57) **CLAIM**

The ornamental design for a dimmer switch, as shown and described.

DESCRIPTION

FIG. 1 is a front perspective view of a dimmer switch showing a first embodiment of our new design.

FIG. 2 is a front elevation view thereof.

FIG. 3 is a right side view thereof.

FIG. 4 is a left side view thereof.

FIG. 5 is a top view thereof.

FIG. 6 is a bottom view thereof.

FIG. 7 is a front perspective view of a dimmer switch according to a second embodiment of the design shown in FIG. 1.

FIG. 8 is a front elevation view thereof.

FIG. 9 is a right side view thereof.

FIG. 10 is a left side view thereof.

FIG. 11 is a top view thereof.

FIG. 12 is a bottom view thereof.

FIG. 13 is a front perspective view of a dimmer switch according to a third embodiment of the design shown in FIG. 1.

FIG. 14 is a front elevation view thereof.

FIG. 15 is a right side view thereof.

FIG. 16 is a left side view thereof.

FIG. 17 is a top view thereof.

FIG. 18 is a bottom view thereof.

FIG. 19 is a front perspective view of a dimmer switch according to a fourth embodiment of the design shown in FIG. 1.

FIG. 20 is a front elevation view thereof.

FIG. 21 is a right side view thereof.

FIG. 22 is a left side view thereof.

FIG. 23 is a top view thereof; and,

FIG. 24 is a bottom view thereof.

The portions of the drawings appearing in broken line are for environment only and do not form a part of the design.
